BALLAST DISTRIBUTOR

Martin J. Speno, Syracuse, and Anthony T. Bruno, East Syracuse, N.Y., assignors to Frank Speno Railroad Ballast Cleaning Co. Incorporated, Ithaca, N.Y., a corporation of New York

Filed July 5, 1962, Ser. No. 207,689
8 Claims. (Cl. 198—46)

This invention relates to a conveying and distributing mechanism which is primarily adapted for use in distributing ballast in various desired ratios to the opposite sides or shoulders of a road bed, though it is by no means restricted to this particular use.

In the maintenance of railroad beds there exists a problem of maintaining equal amounts of stone ballast on the opposite side of the road bed, where shoulders are required for the purpose of maintaining a good track line as well as for maintaining substantially constant level of the track. Inequality of the shoulders on opposite sides of the track most frequently occurs on curves, though it may also occur on straight-aways, particularly where there is a substantial volume of heavy traffic.

It has for many years been the practice to periodically move and clean out the ballast from the shoulders by a transportable ballast cleaning unit carried by a train moving along the track and having means for scooping up the ballast from the opposite sides of the track, sifting and cleaning it to remove the dirt and foreign matter and then returning the clean ballast back to the shoulders. A ballast cleaning machine of this general type is disclosed for instance in the Speno United States Patent 1,951,451 of March 20, 1934.

Prior to the present invention, however, there has been available no mechanized means for transferring surplus ballast from one side of the track to the side having insufficient ballast.

By virtue of the present invention, however, it is made possible, as part of the ballast cleaning operation, to transfer any desired proportion of the cleaned stone coming from one side or shoulder of the road bed to the other shoulder thereof, without interruption of the progress of the ballast cleaning machine along the track and by the use of comparatively simple, economically produced and maintained mechanical equipment.

To this end, separate laterally opposed discharging chutes, preferably opening from a common hopper, are disposed to receive ballast delivered to each by its individual infeed conveyor. For transferring the output of either conveyor in any desired proportion to the discharge chute normally served by the other conveyor, there is provided a transversely moving transfer conveyor operatively positioned at the delivery ends of the respective infeed conveyors and supported for bodily transverse adjustment in such manner as to intercept all or any desired portion of the material delivered by one conveyor, and transfer it into the discharge chute normally served by the other conveyor. In order to permit reversal of the transfer movement, the transfer conveyor itself is reversible. Preferably also the transfer conveyor is mounted for bodily retraction from its operative position so that when its function is not required it may be maintained stored in an inoperative or retracted position.

Further features and advantages of the invention will be apparent from the ensuing detailed description of the invention in conjunction with the accompanying drawings illustrating the preferred embodiment of the invention, in which:

FIGURE 1 is a plan view of a ballast distributing mechanism in accordance with the invention.

FIGURE 2 is a vertical section through the structure of FIGURE 1 along the line 2—2 of FIGURE 1,

2

FIGURE 3 is an end elevation of the structure shown in FIGURES 1 and 2, illustrating diagrammatically the manner in which it is adapted to be supported in operative relation for movement along a railway track to deliver the ballast in controlled amounts to the opposite sides of shoulders of the road bed, and

FIGURE 4 is a detail view showing the preferred manner of associating its reversible motor with the transfer conveyor.

Referring now in detail to the accompanying drawings, the several major elements or components of the invention are but generally or diagrammatically illustrated inasmuch as the several individual components per se are conventional and constitute no part of the present invention apart from the combinations and subcombinations of such elements or components as hereinafter more fully described.

In the drawings, more particularly in FIGURE 3, there are shown the pair of laterally adjoining discharge chutes 10 and 11, which together with the rest of the ballast distributing mechanism are adapted to be transported along the railroad tracks R as by means of a flat car, the arrangement being such that the discharge chutes have laterally outwardly or oppositely directed discharge openings 12 and 13 to which their contents is directed along the inclined bottoms 14 and 15 respectively of the chutes. The arrangement is such that the chutes are disposed to deliver or discharge ballast onto the shoulders, respectively designated S, of the road bed on opposite sides of the track which is comprised of the series of ties T and the respective parallel rails R, as shown in FIGURE 3.

Preferably the two discharge chutes 10 and 11 define the lower portion of a common hopper H, the sides of which extend substantially above the chutes and in which the hopper itself opens upwardly and preferably is of substantially rectangular shape in plan. It will be seen that the two chutes are separated by an upwardly projecting divider 17 which longitudinally bi-sects the hopper midway of its width so that material falling onto the opposite sides of the ridge line or apex 18 of the divider will be caused to fall down one or the other upwardly converging side walls 17' intersecting along said apex for delivery into one chute or the other.

In order to provide rigid supporting means for the structure hereinafter described, there is provided a rigid frame, preferably in the form of a super structure generally designated 20 and which is shown as comprising the opposed longitudinally extending parallel side elements 21 the rear ends of which are interconnected by the rigid crosspiece 22, these interconnected elements being formed of suitable I-beams or other conventional structural units and supported in spaced relation above the upper edges of the hopper as by means of the vertical standards or supports 23 to 25 as shown.

For delivering the ballast into the respective chutes, there are provided a pair of infeed conveyors 26 and 27 respectively having relatively laterally aligned delivery ends 26A and 26B above the respective chutes 14 and 15 for normal delivery by gravity of the ballast or other material discharged from each infeed conveyor into its respective chute. Obviously these infeed conveyors may assume any of various forms, though they may advantageously constitute portions of a ballast cleaning mechanism, each infeed conveyor thus being adapted to receive the ballast picked up from the road bed on its respective side of the track and preferably being formed as a vibrating screen or sifting element of well-known type, sloping downwardly longitudinally from its material receiving end to its delivery end over the hopper. It will be understood that the sloping bottom of each screen is provided with a multiplicity of perforations of uniform size and disposition in accordance with the practice well-known in con-

nection with shifting screens. Its vibratory motion similarly may be caused by conventional means not herein shown.

It will be apparent, that with the elements thus far described, all of the material normally delivered through each infeed conveyor 26, 27 will be directed by gravity into its respective chute 10, 11 from which it will be distributed onto the road bed on the same side or shoulder from which it was originally taken for cleaning.

In order to provide for diverting a portion of the material from either infeed conveyor to the discharge chute normally served by the other such conveyor, there is provided a laterally acting transfer conveyor 30 having means for supporting it in material receiving relation to the infeed conveyors, or as shown in the preferred embodiment, beneath the delivery ends of the respective infeed conveyors, with its material receiving and discharge ends disposed over the respective discharge chutes and across the divider earlier mentioned. As thus disposed, the horizontally extending transfer conveyor 30 will receive a portion of the material delivered by one infeed conveyor and transfer such material to the discharge chute normally served by the other such conveyor. In the present embodiment the transfer conveyor is exemplified by a flexible endless belt or apron 31 guided for movement in an endless circuit around rolls 32 and 33 supported at the opposite ends of a rigid frame which includes the rigidly interconnected parallel side rails 34 and 35, each of which preferably supports an upwardly projecting side wall or guide 36, 37 for confining the material on the upper operative run of the belt.

It is an important feature of the invention that the transfer conveyor, whatever form it may assume, be provided with reversible drive means whereby it may be caused to convey material in either direction and thus in effect the reversible drive means may serve to relatively interchange the functions of the receiving and discharging ends respectively of the conveyor. In the instant embodiment the reversible drive means is in the form of a reversible electric motor 38 preferably housed within the conveyor frame on the inner face of one of the side conveyor frame members or rails 34, with its output shaft 39 rotatably extending through said rail and connected by means of a flexible drive 40 to the shaft 41 of one of the conveyor rolls 32. In addition to being reversible, the driving motor 38 in the instant embodiment also is of the conventional variable speed type, whereby its operational speed may be adjusted and coordinated with the operational speed of the other associated conveyors and components of the invention.

The supporting means for the transfer conveyor 30 provides for bodily lateral adjustment of the said conveyor, so that its receiving end may be selectively positioned for reception of varying proportions of the material delivered by the particular infeed conveyor with which said receiving end may be associated. At this point it will be appreciated that either end of the infeed conveyor may be made to function as its receiving end and the other end as its discharge end, depending simply on the direction in which upper run of the flexible conveyor is driven by its reversible driving motor 38.

The specific means herein employed for thus supporting the transfer conveyor comprises an I-beam 42 which extends between and is supported by the respective side members 21-21 of the super structure to define a horizontal trackway on which is disposed a laterally movable trolley or slide 43 having rigid suspension arms 44 depending therefrom and fixedly connecting to the conveyor frame on the side thereof remote from the delivery ends of the infeed conveyors to avoid interference with the infeeding action. In other words, the transfer conveyor is supported from one side only, whereby its other side may remain completely free and unobstructed to avoid interference with the material issuing from the delivery ends of the respective infeed conveyors.

The trolley 43 itself includes interconnected opposed side plates adapted to depend on opposite sides of the I-beam and rotatably supporting rollers 45 which are received in the oppositely facing channels on opposite sides respectively of the I-beam.

Power means preferably is provided for selectively causing the lateral adjustment of the conveyor trolley and the transfer conveyor, such means comprising the double acting hydraulic cylinder and piston unit 46, having the free end of its piston rod connected to the trolley frame by means of the cross bar 47 extending between and connected to the respectively outwardly projecting bracket portions 48 of the trolley side plates.

Although in normal operation, the transfer conveyor 30 will be positioned as shown in full lines in FIGURES 1 and 2, adjacent and beneath the delivery ends of the respective infeed conveyors, there will normally be times when its use is not required. During such times it will obviously be desirable to permit retraction of the transfer conveyor from its operative position to an inoperative storage position. To this end, the opposite ends of the trolley guide rail or support 42 are disposed and guided for sliding movement along the longitudinally extending super structure rails or members 21, by means of the trolleys or slides 49 to which the ends of the guide rail 42 are rigidly affixed. Each of these slides preferably is of inverted U-shaped cross section having trolley sheets 50 rotatably supported from its depending sides for rolling movement in and along the oppositely presented lower flanges of the respective I-beams.

For moving the guide rail and transfer conveyor 30 between operative and inoperative positions, there is provided a double acting hydraulic piston and cylinder unit 51 in which the base of the piston is fixed to a bracket 52 projecting upwardly from the super structure member 22 while the free end of the piston rod of such unit is connected to the rail 42 by means of the clevis connection 53 illustrated. The side plates of the trolley 43 are interconnected across the top of the rail 42 only by the cross bar 47, all other cross connections 54 extending beneath the rail to avoid obstruction of the trolley movement by the clevis 53 or unit 51.

In the operation of the invention, in its preferred use in association with a ballast picking up and cleaning unit, the two infeed conveyors 26, 27 will normally be forwardly directed and each adapted to receive the ballast picked up from the shoulder of the roadway on its respective side of the railroad track, it being understood that there will be employed suitable pickup means and conveyor mechanisms delivering the ballast from each side of the track onto its respective infeed conveyor. In the event the ballast has already been cleaned at the time of its deposit onto the infeed conveyors then these elements need only be adapted to perform their conveying function. However, they may equally well be adapted to perform the added function of screening out the dirt and foreign materials from the ballast, where the infeed conveyors assume the form of vibrating screens as in the preferred embodiment. The material delivered from the delivery ends of the respective conveyors falls at least partially on and is intercepted by the transfer conveyor. The transfer conveyor may be driven in either direction to divert the said material from either conveyor into the discharge chute normally receiving the entire discharge of the other said infeed conveyor. The relative proportion of the diverted material, with respect to the entire delivery of the particular infeed conveyor from which it is diverted, may be selectively varied in obvious manner by lateral adjustment of the position of the transfer conveyor through appropriate control of its hydraulic positioning unit 46. Where the functioning of the transfer conveyor is not desired, it may be retracted from its operative position by actuation of the hydraulic piston and cylinder unit to retract not only the transfer conveyor but also its supporting trolley 43 and guide rail

42. Thus all of these may be stored in an out of the way position at the rear of the hopper and remote from the delivery ends of the infeed conveyors so as to avoid obstructing the flow of material therefrom. However, the transfer conveyor may be restored to its operative position adjacent and beneath the infeed ends of the infeed conveyors whenever desired by appropriate action of the hydraulic unit 51.

There is shown and described in this application only the preferred embodiment of the invention, although it is recognized that the invention is capable of other and different embodiments and that its several details may assume varying forms, all without departing from the invention as defined in the appended claims. Having thus described our invention, we claim:

1. A ballast distributing mechanism comprising a pair of laterally adjoining discharge chutes, a pair of simultaneously operative infeed conveyors having relatively laterally aligned delivery ends positioned above the respective chutes for normally simultaneous delivery by gravity of the material from each infeed conveyor directly into its respective chute, a laterally acting transfer beneath said infeed conveyors, said transfer conveyor having material receiving and discharging ends respectively over different said chutes to thus receive a portion of the material delivered by one infeed conveyor and transfer it to the discharge chute normally served by the other infeed conveyor, reversible drive means for said transfer conveyor for relatively interchanging the functions of its receiving and discharging ends respectively, and means supporting said transfer conveyor for bodily lateral adjustment whereby its receiving end may be selectively positioned for reception of varying proportions of the material delivered by one of said infeed conveyors, the distance between said receiving and discharging ends being substantially less than the lateral distance between the relatively remote sides of the infeed conveyors to permit a wide range of adjustment of the transfer conveyor while nevertheless retaining its discharging end in position above and for delivery of the material from said one infeed conveyor into the chute normally served by the other said infeed conveyor.

2. A ballast distributing mechanism as defined in claim 1, including power means operatively connected to said transfer conveyor for selectively adjusting its lateral position.

3. A ballast distributing mechanism as defined in claim 2, including means supporting said transfer conveyor for longitudinal horizontal movement toward and away from said delivery ends of the infeed conveyors, and power means for causing such movement.

4. A ballast distributing mechanism comprising a pair of laterally adjoining and simultaneously operating discharge chutes, a pair of infeed conveyors having relatively laterally aligned delivery ends above the respective chutes for normal delivery by gravity of the material from each infeed conveyor directly into its respective chute, a laterally acting transfer conveyor beneath said infeed conveyors, said transfer conveyor having material re-

ceiving and discharging ends respectively over different said chutes, to thus receive a portion of the material delivered by one infeed conveyor and transfer it to the discharge chute normally served by the other infeed conveyor, and means supporting said transfer conveyor for bodily lateral adjustment to any of various positions partially across the path of delivery of material from said one infeed conveyor, the distance between said receiving and discharging ends of the transfer conveyor being appreciably less than the distance between the relatively remote sides of said infeed conveyors.

5. A ballast distributing mechanism as defined in claim 4, including means supporting said transfer conveyor for longitudinal movement from its operative position to a retracted inoperative position remote from said delivery ends of the infeed conveyors.

6. A ballast distributing mechanism comprising a pair of laterally adjoining discharge chutes, a pair of infeed conveyors having relatively laterally aligned delivery ends above the respective chutes for normal delivery by gravity of the material from each infeed conveyor into its respective chute, a rigid supporting super structure above said chutes, a rigid laterally extending horizontal guide rail carried by said super structure, a trolley guided for lateral movement along said rail, a laterally extending transfer conveyor having a horizontal conveyor portion supported by said trolley for bodily lateral adjustment with said trolley, said transfer conveyor having an operative conveyor portion disposed beneath the delivery ends of said infeed conveyors, said portion having laterally opposed material receiving and discharging ends respectively over different said chutes, to thus receive a portion of the material delivered by one infeed conveyor and transfer it to the discharge chute normally served by the other infeed conveyor.

7. A ballast distributing mechanism as defined in claim 6, including reversible drive means for said transfer conveyor for relatively interchanging the functions of its receiving and discharging ends respectively.

8. A ballast distributing mechanism as defined in claim 7, including means supporting said guide rail for longitudinal movement on said super structure, and power means interconnected between said super structure and said guide rail for longitudinally moving the said guide rail to retract the transfer conveyor to an inoperative storage position remote from the delivery ends of the respective infeed conveyors.
